STATIONARY CONDENSER

William P. Dooley, South Charleston, W. Va., assignor to American Viscose Corporation, Philadelphia, Pa., a corporation of Delaware

Application April 28, 1953, Serial No. 351,676

3 Claims. (Cl. 183—57)

The present invention relates to a novel and improved means for condensing or separating fibrous materials from suspensions thereof in air or other gaseous medium. More particularly, the present invention relates to a novel and improved fiber condensing device of such construction that undue fiber accumulation adjacent moving parts is effectively eliminated.

In the textile art, the so-called "fiber condenser" is, in many of the fiber processing operations, a very useful and oftentimes essential piece of apparatus. It is commonly employed to filter the various fibrous materials from a turbulent body or stream of air in which they are carried or suspended. Thus, for example, in conveying fibers from a conventional fiber-opening or other fiber-handling operation to a subsequent stage of operation, such as packaging, relatively brisk currents or blasts of air are oftentimes used and a fiber condenser is employed to settle or condense the fibers at the desired point of destination so that they can be readily processed thereafter in bulk or packaged, such as by baling.

In a similar manner, the fiber condenser finds ready application in fiber drying, mixing, blending, and many other textile processing operations where currents or blasts of air or the like are applied to the fibrous material.

Fiber condensers used prior to the present invention commonly consisted of a perforated drum rotatably mounted in a casing to which the air-blown fibers are supplied. The interior of the drum is ordinarily divided into a suitable number of sections by a plurality of stationary valve plates or baffles which are secured one to the other adjacent the axis of the drum and project in a radial manner therefrom. At any given instant during rotation of the drum, some of the radial sections of the drum interior are connected to a suitable source of suction while others are not. Thus, as the drum rotates at a predetermined rate about the various stationary radial sections thereof, the air-blown fibers delivered to the casing are successively collected and discharged from the periphery of the drum. Considerable difficulty has been experienced in preventing stray fibers from short-circuiting the evacuated interior portions of the drum and collecting adjacent its bearings in the casing thereby impeding its free movement and creating a fire hazard.

It is a principal object of the present invention to provide a novel and improved fiber condenser wherein the undesired collection of stray fibers and the like adjacent its moving parts is substantially eliminated.

Other objects and advantages of the present invention will be apparent from the following description.

In the drawing, which is illustrative of the improved fiber condenser,

Figure 1 is a section on reference line I—I in Figure 2 of one embodiment of the present invention;

Figure 2 is a section on reference line II—II in Figure 1; and

Figure 2a is a perspective of a driving system.

2

In general, the improved fiber condenser of the present invention comprises an enclosed chamber with a fiber collecting screen defining a wall portion thereof, means for delivering air-blown fibers to the chamber, and means externally of the chamber for alternately collecting the fibers on, and discharging the fibers from the screen. It has been found that in the use of such a device, the above-mentioned undesired collection of stray fibers adjacent its moving parts is effectively minimized. More particularly, preferred embodiments of the invention are concerned with apparatus for condensing fibers suspended in a gaseous fluid. Such apparatus comprises a receptacle, the upper wall of which has a plurality of fiber collecting screens spaced from each other. A discharge outlet for the receptacle is connected to the bottom thereof. Means are provided for introducing a fiber suspension into the receptacle, and means are provided for periodically enclosing a region above each fiber collecting screen or pervious portion. Suitable mechanisms are also provided for alternately subjecting each enclosed region to suction and pressure to collect the fibers on the screens and to discharge the fibers from the screens.

One preferred embodiment of the present invention is shown in Figures 1 and 2 of the drawing. As illustrated therein, the air-blown fibers are supplied from a source not shown on the drawing and conducted upwardly through the conduit or the like 3 into the enclosed chamber or receptacle 4. The chamber is preferably constructed as a hopper having steep side walls to reduce the tendency of the fibers to cling thereto. The discharge outlet 4a at the bottom of the hopper extends downwardly to a suitable fiber-collecting means such as to a feed hopper for a baling press (not shown).

The condenser comprises a valve assembly generally designated as 5 and is preferably but not necessarily positioned above the hopper-like chamber 4 as shown in Figure 1 of the drawing. Accordingly, its housing member 6 is secured as by cap screws 7 and a gasket, if desired, to the top of the chamber 4. The housing partition member 8 is secured, such as by the screws 9, to the ceiling of the housing 6 and extends downwardly therefrom, providing a support for a stationary cylindrical member 10 of the valve assembly 5. Top partition 8 and the diametrically disposed bottom partition 8a and member 10 divide the space within housing 6 into two compartments 11 and 12 preferably of about equal volumetric size. Fiber collectors 13 and 14, which may comprise fine-mesh screens, extend between the sides of partition 8a and the sides of the housing 6.

The cylindrical member 10 is enclosed at its opposite extremities as shown in Figure 2 of the drawing such as by the end plates 15 and 16 secured to the member 10 by screws, the juncture therebetween being sealed by a gasket. The bearings 17 and 18 which are centrally positioned in the end plates support a fixed elongated tubular hollow shaft 19 which extends through the interior of the cylindrical member 10 and is closed at one end by a cap 39.

A hollow shaft or sleeve 20 carrying radially extending plates 21 and 22 is rotatably mounted on the shaft 19 between axially spaced collars 23 and 23a fixed on the shaft 19. Drive gear 38 is secured to shaft 20. The plates 21 and 22 divide an intermediate portion of the interior of the cylindrical member 10 into the two semi-cylindrical sections 24 and 25 to which suitable sources of pressure and suction may be respectively connected. Semi-circular plates 29 and 30 are secured to or made integral with the shaft 20 and project radially therefrom on one side of and between plates 21 and 22. Plates 29 and 30 are disposed at positions spaced axially inward from the closed ends 15 and 16 and approximately

in alignment with the end walls **6a** and **6b** of housing **6**. The perforations **10a** of member **10** are located entirely in the peripheral zone of such member that lies between the planes of plates **29** and **30** regardless of how far such plates are spaced from walls **6a** and **6b**. The perforations must also be disposed entirely between end walls **6a** and **6b** of the housing **6**, a conduit **28** is connected to each end zone **26** and **27** which zones are surrounded by non-perforated peripheral bands of the member **10**. A source of suction is connected to conduits **28** which suction pulls air from the ends of the cylindrical member **10** whereby reduced pressure can be produced in whichever half of the perforated zone of member **10** (24 in the position shown in Figs. 1 and 2) which is in communication with end zones **26** and **27**.

The semi-circular end plates **29** and **30** which are positioned at each end of the sleeve member **20** serve with plates **21** and **22** to isolate one of the sections **24** and **25** from the other section and from the end chambers or zones **26** and **27**. When one of the sections **24** or **25** is so isolated, the suction pull through that section is cut off. One or more weights **20a** may be secured to shaft **20** to counterbalance the plates **29** and **30**. In the position shown in Figure 1, section **25** is thus isolated and section **24** of the cylindrical member **10** is in communication with end zones **26**, **27** and conduits **28** to the suction source or sources. The enclosed or isolated section (**25** in the position shown) of the cylindrical member is adapted to be connected to any suitable source of pressure not shown on the drawing through apertures **34** in the portion of shaft **20** between plates **29** and **30**, one of the diametrically opposite sets of apertures **34a** in fixed shaft **19**, and the bores of shaft **19**, flanged coupling **33**, and pipe **31**, the latter being controlled by the valve **32**.

The valve **32** in the pressure line **31** is normally urged to close the line by a spring **32a** which acts against a collar on the solenoid core **35** pivotally connected to a lever **35a** which swings the valve core.

Any suitable means may be provided for intermittently rotating the shaft **20** with its plates **21**, **22**, **29** and **30** which in effect form a semi-cylindrical valve core within the perforated zone of the cylindrical member **10**. This rotating means is also operatively connected with means for momentarily introducing pressure into the isolated section (**24** or **25**) within the plates **21**, **22**, **29** and **30**. This rotating means comprises an electric motor **85** (see Figure 2a) connected in a circuit comprising lines **86** and **87** connected to a source of power indicated by the legend "Line." A master switch **88** is provided to start and stop the motor **85**. During operation of the machine, the switch **88** remains in closed position and the motor **85** is driven continuously at a constant rate of speed and is connected through a reduction gear box **89** to a timing cam **90**. The rise of this cam **90** is adapted to close a switch **91** at periodic intervals. This switch **91** is connected in series with the "Line" and the solenoid **92** of a relay having a retractable core **93** which during periods of deenergization of the solenoid **92** is urged in a suitable manner such as by spring means or by gravity, as shown, into engagement with the notched control disc **94** of a single revolution clutch **95** the driving element of which is driven continuously by a motor **96** which may also be connected to the "Line" by a circuit not shown. Closure of the switch **91** causes retraction of the core or latch **93** and the rotation of shaft **97** for a single revolution, the shaft at the completion of one revolution being stopped by the re-engagement of the disc **94** by the latch **93**. The shaft **97** carries fixedly secured thereon for rotation therewith a gear **98** having half the number of teeth as the gear **38** with which it is in mesh so that a single revolution of gear **98** effects a half revolution of the shaft **20**. A cam **99** is fixedly mounted on shaft **97** and its rise is adapted to close the contacts of switch **100** within a circuit comprising the solenoid **36**. The switch **100** and

the rise of cam **99** are so disposed on shaft **97** that solenoid **36** is energized near the completion of each half revolution of the shaft **20**. Preferably, switch **100** is reopened to de-energize solenoid **36** upon the completion of the half-revolution for reasons explained more fully hereinafter.

In operation, the various parts of the system may be assumed to be disposed in the relationship shown in Figures 1 and 2. The gaseous suspension of fibers enters the chamber **4** through the conduit **3** and is sucked up against the perforated screen **13** by virtue of the fact that reduced pressure is communicated into the region **12** through the apertures on the left side of cylindrical member **10** (as viewed in Figure 1). The reduced pressure within the left half of cylindrical member **10** is communicated thereto through the end chambers **26** and **27** and the suction conduits **28**. After a predetermined time interval, a reasonably thick blanket of fibers is collected on the screen **13** and the cam **90** closes the switch **91**. The frequency of closure of switch **91** is determined by selection of the speed of the motor **85** and the reduction gear **89** and these details are selected in accordance with the density and rate of flow of the fiber suspension. Upon the closure of switch **91**, latch **93** is retracted and the single-revolution clutch **95** rotates gear **98** through a single revolution which rotates gear **38** and shaft **20** through a half-revolution so that the valve assembly comprising shaft **20** and plates **21**, **22**, **29** and **30** is rotated from the position shown to a position 180° therefrom. Near the end of that half-revolution, cam **99** closes switch **100**. This energizes solenoid **36** and opens valve **32**, connecting the high pressure line **31** to the bore of shaft **19** and causing a sudden increase in pressure within the isolated chamber **24** defined by plates **21**, **22**, **29** and **30** and the perforated wall at the left of cylindrical member **10** as viewed in Figure 1. This high pressure is communicated from the zone **24** through the apertures **10a** to the region **12** which causes the mat of fibers held against the screen **13** to be suddenly released and to fall downwardly to the collection receptacle. The setting of cam **99** may be so disposed that the introduction of the high pressure air into the zone **24** occurs as partition **22** passes the uppermost row of the perforations **10a** on the left hand side of cylindrical member **10**, such row of perforations being spaced from the top of the member **10** by an unperforated strip of substantial width **x**. For example, this may be effected when partition **22** passes through the dotted line position shown. Similarly, on the next half revolution, air pressure would be admitted to chamber **25** as the plate **22** swings beyond the lowermost row of perforations on the right hand side of the member **10**, such as indicated by the dotted lines in Figure 1. This row is spaced from the bottom of the member **10** by an unperforated strip **y** of width similar to that of **x** above. As stated above, switch **100** is reopened at or just prior to the completion of the half-revolution of shaft **20** since it is undesirable to have high-pressure air continually introduced through either of the screens **13** and **14** after the release of a fiber mat from one of them. During the half-revolution of the isolating valve within member **10**, the suction which is continuously applied through conduits **28** is gradually transferred from one region such as from region **12** to the other region, such as region **11** and, of course, at the completion of the half-revolution of the isolating valve core, the suction is continuously applied to the back of the new screen surface, such as at **14** in the instance just mentioned.

Thus, fibers are alternately collected on one of the screens **13** and **14** and alternately discharged from such screens after building-up to predetermined thickness during predetermined time intervals controlled by the cam **90**. All of the moving parts in the system are spaced back of the collecting screens **13** and **14**, thereby avoiding the tendency of fibers to be side-tracked through the spaces

between relatively moving parts as occurred in prior devices where the collecting screen itself was moved.

While a preferred embodiment of the invention has been disclosed, the description is intended to be illustrative only and it is to be understood that changes and variations may be made without departing from the spirit and scope of the invention as defined by the appended claims.

I claim:

1. Apparatus for condensing fibers suspended in a gaseous fluid comprising a chamber having a pervious wall, a fiber introducing conduit connected with the chamber, a housing enclosing the pervious wall of the chamber, end plates for the housing, a perforated cylindrical member within the housing, a mounting for the cylindrical member, the cylindrical member and its mounting dividing the housing into a pair of compartments, a hollow fixed shaft within the cylindrical member which shaft lies concentrically with the member and is supported by the housing end plates, one end of said shaft being connected with a pressure source, a tubular shaft rotatably mounted on the fixed shaft, radially and axially extending plates secured to the tubular shaft which plates extend into close clearance with the inner periphery of the cylindrical member to divide the interior of the cylindrical member into two compartments, two semicircular plates secured to the rotatable tubular shaft at points spaced inwardly from the housing end plates and extending radially to the inner periphery of the cylindrical member, said axially extending plates and semicircular plates forming with the shaft an isolation valve adapted to divide an intermediate zone within the cylindrical member into two semicylindrical sections isolated from one another and to provide end chambers in the cylindrical member which communicate with only one of the semicylindrical sections, the periphery of the cylindrical member being perforated in the intermediate zone only; means for intermittently rotating the tubular shaft, suction conduits leading into the end chambers, apertures in the fixed hollow shaft and in the rotatable tubular shaft for providing intercommunication between the bore of the fixed shaft and the semicylindrical section of the cylindrical member which is not in communication with the end chambers whereby air under pressure may be introduced into the non-communicating section of the cylindrical member a normally closed valve positioned in the hollow shaft; and means for periodically opening the valve.

2. An apparatus for condensing fibers which are suspended in a gaseous fluid comprising a chamber having a pervious wall, a fiber introducing conduit connected with the chamber, a housing positioned over the chamber and enclosing the pervious chamber wall, end plates for the housing, a perforated cylindrical member positioned

within the housing, a mounting for the cylindrical member, said cylindrical member and mounting dividing the housing into two compartments, suction conduits leading into the housing interior adjacent the housing end plates whereby air may be withdrawn upwardly through the pervious wall of the chamber into the housing and the cylindrical member and outwardly through the ends of the cylindrical member to draw the fibers against the pervious chamber wall, means within the cylindrical member supported by the housing end plates for alternately directing air under pressure into each compartment to blast the fibers from the pervious chamber wall, and intermittently rotating closure plates secured to the means for supplying air under pressure for alternately closing off the suction through one-half of the cylindrical member.

3. An apparatus for condensing fibers which are suspended in a gaseous fluid comprising a chamber having a pervious wall, a fiber introducing conduit connected with the chamber, a housing positioned over the chamber and enclosing the pervious chamber wall, end plates for the housing, a perforated cylindrical member positioned within the housing, a mounting for the cylindrical member, said cylindrical member and mounting dividing the housing into two compartments, suction conduits leading into the housing interior adjacent the housing end plates whereby air may be withdrawn upwardly through the pervious wall of the chamber into the housing and cylindrical member and outwardly through the ends of the cylindrical member to draw fibers against the pervious wall of the chamber, a hollow shaft extending through the cylindrical member and supported by the end plates, diametrically opposed apertures in the shaft opening into each compartment, an apertured rotatable sleeve mounted on the shaft, means for intermittently rotating the hollow shaft, said apertures of the rotatable sleeve being adapted to lie in alignment with the shaft apertures when the sleeve is at rest whereby air under pressure may be alternately introduced within each compartment of the cylindrical member through the hollow shaft and the sleeve apertures to blast the fibers from the pervious wall, and closure plates secured to the rotatable sleeve for alternately closing off the suction through one-half of the cylindrical member.
